UNITED STATES PATENT OFFICE.

JOSEPH G. AYERS AND WILLIAM H. CHAPMAN, OF MONTCLAIR, AND MAX E. BERLOWITZ, OF BELLEVILLE, NEW JERSEY, ASSIGNEES TO GENERAL MOTORS CORPORATION, OF DETROIT, MICHIGAN, A CORPORATION OF DELAWARE.

GAUGING MACHINE.

Application filed April 7, 1924. Serial No. 704,692.

This invention relates to gauging machines and is herein shown as embodied in a machine for gauging the lengths of cylindrical rollers.

One well known form of roller bearing comprises cylindrical rollers sleeved on tie bars connecting the sides of a cage. These rollers must conform to certain tolerances as to length but hitherto gauging has been slow, necessitating the separate handling and gauging of each roller by a snap gauge or the like. One of the objects of this invention is to provide a machine for rapidly gauging cylindrical rollers or like articles. Another object is to provide a machine for automatically gauging such articles and for segregating those that conform to acceptable limits. Another object is to provide an accurate and efficient gauging machine which will eliminate the human element or personal equation.

To these ends and also to improve generally upon devices of the character indicated our invention consists in the various matters hereinafter described and claimed.

In the drawings, Figure 1 is a vertical section, partly broken away, of the gauging machine.

Figure 2 is a plan view of the face plate or inclined support with some of the parts omitted and some in a different position from that shown in Figure 1.

Figure 3 is an end view of the face plate.

Figure 4 is a front elevation of the machine with the face plate removed.

Figure 5 is a detail view of one of the gauge blocks.

Figure 6 is a section on the line 6—6 of Figure 5.

Figure 7 is a vertical section on Figure 4 showing some of the parts in side elevation.

Figure 8 is a plan view of the frame with the face plate and other parts removed.

The numeral 10 designates the frame, the upper edges of which are inclined to receive an inclined face plate or article support 12 positioned on the frame by dowel pins 14 and fastened by screws 16. Cut through the face plate are a series of gauge slots 18, each slot having four sides and having one dimension, herein the width, larger than the width or diameter of the articles to be tested. One side of each slot has a vertical positioning surface 20 and the opposite side

22 has an interrupted surface parallel to the surface 20. The top face of the plate 12 forms a runway down which the articles roll and this face merges with an incline 24 leading to the slot. The face plate is also cut out at intervals as at 26 to admit swinging articles aligning or pressing means to be later described. Longitudinal guide bars 28 extend over the face plate and are secured by screws to slotted plates 30 adjustably fastened to the sides of the face plate by screws 32. The bars 28 are spaced apart a distance a little greater than the lengths of the rollers R or other articles to engage the ends of the same and guide them to the gauge slots.

The shorter sides of the slots are formed by gauge blocks 34 having inclined faces 36 leading to the vertical gauging faces 38. Each block has projections or tongues 40 received in ways cut in the under side of the face plate and the tongues are slidably held by plates 42 having portions overhanging the tongues. The distance apart of the gauge faces 38 varies at the different slots, the first set of gauging faces being spaced a shorter distance apart than the succeeding set. The gauge blocks are adjusted towards each other by adjusting screws 44 threaded in the sides of the face plate and abutting against the outside faces of the gauge blocks. The articles that are shorter than the acceptable size are eliminated at the first gauging slot and the others pass to the succeeding slot for a further test. If they are of acceptable size, they drop through this slot but, if too long, they are rejected as will hereinafter appear.

If articles are merely allowed to roll down an incline to a gauging slot, they will not properly gauge themselves particularly if they are rollers formed of helically wound steel. Accordingly means is provided for aligning them with the slots and pressing them uniformly against the gauging surfaces. This is accomplished by swinging arms 50, the hubs 52 of which are secured to rock-shafts 54 extending across the face plate and supported in bearings 56. When the arms 50 are depressed against the articles, they force the latter against the sides 20 of the gauge slots and straighten them out and likewise press the ends of the articles down the inclines 36 on the gauge

blocks to the gauging surfaces 38. Each arm 50 has at its end an arcuate bar 58 forming an interrupter or obstructor so that when the arms 50 are depressed against one of the articles, the following article rolling down the support will be prevented from interfering with the gauging operation. The ends of the arms 50 enter the cut-out portions 26 in the face plate and hence are able to engage the side of an article and press it against the side 20 of the slot. The arms are yieldingly pressed downwardly by springs 62 attached at one end to the frame and at their other ends to arms 60 fastened to the ends of the rock-shafts 54.

The arms 50 are raised and lowered by the following mechanism. Journalled near the bottom of the frame is a crank shaft 66 joined by a connecting rod 68 to a wrist pin 70 on a slide or cross head 72. A plate 74 at one end of the cross head is fastened to a slide plate 76, the inner face of which bears against a guide plate 78 having tongues 80 entering slots in the frame and fastened by pins 82 driven into the slots. A second slide plate 84 is fastened by screws 86 to the cross head and bears against a guide plate 88 having tongues 90 entering slots in the frame and fastened by pins 92. Also actuated by the cross head, is a cam carrier 94 having its ends received in slots 96 in the frame. To the upper end of each slide 76 and 84 is secured a blade or lifter 64 which reciprocates through one of the gauging slots and has its upper end rounded as at 98 to form a cam face which, if the article is not eliminated in the gauging operation, lifts it from the slot and directs it downwardly to the succeeding slot. The blades 64 also lift the swinging arms 50 against the tension of the springs 62 and their forward faces act as stops for the articles as they roll down the inclined support. When one of the articles is stopped by the front face of a blade 64, it is held in this position until the blade has been lowered out of the slot and, simultaneously, the arms 50 are lowered to press the article into the slot. Thereafter the arcuate bar 58 obstructs the following article.

When an article has been lifted from one of the slots and directed down the incline, it engages a straightening member 100 consisting of a bent plate attached to the hub 52 by a screw 102, a coil spring 104 between the head of the screw and the member 100 allowing the latter to yield if an article gets under it. The straightening member 100 keeps the articles squarely across the runway and insures their proper delivery parallel to the following gauge slot. If an article is too small, it is eliminated at the first slot and drops down into a chute 106 which conveys it to a receptacle at one side of the machine. If the article is of acceptable size,

it continues on to the second slot and passes through the same and is conveyed to the other side of the machine through a chute 108. If the article is too long, it continues on down the incline and passes out through a chute 110 to the rear of the machine. The chutes 106 and 108 are secured to the sides of the frame by struck up lugs 112 fastened by screws 113. Any desired number of gaugings may be made by providing the necessary number of slots and article moving means.

The mechanism for delivering the articles one by one and rolling them down the inclined support will now be described. The rollers R, or other articles, slide in end to end relation down an inclined feed tube 114 to a delivery recess 116. They are intermittently released to slide into the recess by a detent 118 the end of which enters a hole in the feed tube to engage the side of one of the articles to clamp it against the interior of the tube. The detent is adjustably fixed to an arm 120 pivoted to a fixed pin 122 on the front of the machine and a screw 124 is threaded in the arm and connected to the frame by a spring 126 which tends to move the arm and its detent into article engaging position. The arm is moved against the tension of the spring by a roller 128 journaled in a lug on the arm and cooperating with a cam 130 fastened to the upper end of the reciprocating cam carrier 94 above mentioned. When the detent 118 releases the stream of articles and allows one of them to slide into the delivery recess 116, the article is next carried part way down the runway by a feed member or carrier 132 having a curved article receiving portion or hook 134 movable into and out of alignment with the feed tube. The member 132 is carried by an arm 136 the lower end of which is pivoted to the pin 122. A second arm 138 is pivoted to the pin 122 and is normally pressed against the arm 136 by a coil spring 142. A screw 140 is secured to arm 136 and passes through an opening in arm 138 and the spring 142 abuts at one end against the head of the screw and at the other end against a washer 144 bearing against the arm 138.

The arm 138 and the arm 136 are collectively moved in one direction by springs 148 fastened to the frame and to the ends of a long bar 146 fastened to the arm 138. The arm 138 and the arm 136 can be collectively moved in the opposite direction, or the arm 138 can be individually moved, by means of a roller 150 journaled in lugs projecting from the arm 138 and actuated by a cam 152 on the cam carrying member 94. When the cams 130 and 152 are lowered, the detent 118 locks the stream of articles in the tube and simultaneously therewith, or immediately thereafter, the feed member or carrier 132

carries the endmost article R from the recess 116 part-way down the incline and then the hook portion 134 rides far enough from the top of the face plate to release the article. When the cams rise, the feed member or carrier is brought back into alignment with the feed tube and simultaneously therewith, or immediately thereafter, the detent is moved back to release the stream of articles and allow the endmost article to again move into the hook portion of the carrier. If one of the articles does not fully slide into the recess 116, the carrier on its return, will be stopped by the article, but no damage can occur because the arm 138 can yield independently against the tension of the spring 142.

When the endmost article in the stream slides into the recess 116 it abuts against the end of a locating plug 156 fastened in a sleeve 154. A collar 158 is adjustably fastened by a set screw 160 to the plug and abuts against a collar 162 on the sleeve 154. The plug can be fastened by means of a hand screw 164 in such a position that the end face of the plug is in alignment with the inner face of one of the guide bars 28. The guide bars 28 are preferably bevelled at their ends to guide the articles to the guiding surfaces.

In operation, as the articles roll one by one down the inclined support, they are successively stopped by the blade or lifter 64. As the blade 64 is lowered through the slot, the articles is let into the slot and pressed against the gauging surfaces by the arms 50. The following article is meanwhile obstructed by the arcuate member 58. If the gauged article is not eliminated through the slot, it is lifted by the blade and directed down the incline to the next slot. The straightening member 100 holds the article temporarily and insures its delivery parallel to the next slot where the gauging operation is repeated. Any desired number of gauging operations may be effected by supplying the necessary number of slots and article operating means and the articles of any given size can be segregated by leading them down a suitable chute to a receptacle.

Although the invention has been described by reference to a specific apparatus, it should be understood that, in its broader aspects, it is not limited to the structure selected for illustrative purposes.

We claim:

1. In a gauging machine, a support having a series of slots, with opposite gauging surfaces successively further spaced from each other at the succeeding slots, and means for pressing an article against the gauging surfaces; substantially as described.

2. In a gauging machine, a support having a series of slots with opposite gauging surfaces successively further spaced from

each other at the succeeding slots, means for pressing an article against the gauging surfaces at the first slot, and means for moving the article from the gauging surfaces and directing it to the next slot; substantially as described.

3. In a gauging machine, a support having a series of slots with opposite gauging surfaces which are further apart at the succeeding slots, an arm, and means for swinging the arm against an article to press it into contact with said gauging surfaces; substantially as described.

4. In a gauging machine, a support having a series of slots with opposite gauging surfaces which are further apart at the succeeding slots, an arm, means for swinging the arm against an article in contact with said gauging surfaces; and means for moving said article from said gauging surfaces and directing it to the succeeding gauging surfaces; substantially as described.

5. In a gauging machine, a support having a series of slots with opposite gauging surfaces which are further apart at the succeeding slots, an arm, means for swinging the arm against an article in contact with said gauging surfaces, and a member movable against said arm to lift the same and having a cam to direct the article to the succeeding slot; substantially as described.

6. In a gauging machine, a support having a series of slots with opposite gauging surfaces, the gauging surfaces being further spaced from each other at the succeeding slots, an arm, means for pressing the arm against an article at one of the slots, a reciprocating member for lifting said arm, said member having a cam to direct the article to the succeeding slot; substantially as described.

7. In a gauging machine, a support having a series of slots with opposite gauging surfaces, the gauging surfaces being further spaced from each other at the succeeding slots, an arm having one portion to press against an article at one of the slots and another portion to obstruct the next article, and means for lifting the arm to allow the next article to pass; substantially as described.

8. In a gauging machine, a support having a series of slots with opposite gauging surfaces the gauging surfaces being further spaced from each other at the succeeding slots, an arm having one portion to press against an article at one of the slots and another portion to obstruct the next article, and a member reciprocable through the slot to lift the arm; substantially as described.

9. In a gauging machine, a support having a series of slots with opposite gauging surfaces, the gauging surfaces being further spaced from each other at the succeeding slots, an arm having one portion to press

- against an article at one of the slots and another portion to obstruct the next article, and a reciprocating member to lift the arm, said member operating through the slot and having a cam face to direct the gauged article to the next slot; substantially as described. 5
10. In a gauging machine, a support having a series of slots with opposite gauging surfaces, the gauging surfaces being further spaced from each other at the succeeding slots, an arm having one portion to press against an article at one of the slots and another portion to obstruct the following article, and a member movable with the arm for subsequently straightening the first article for a further gauging operation; substantially as described. 10
11. In a gauging machine, a support having a series of slots with opposite gauging surfaces, the gauging surfaces being further spaced from each other at the succeeding slots, an arm having one portion to press against an article at one of the slots and another portion to obstruct the following article, and a reciprocating member for lifting the arm to release said following article, and a member movable with the arm for straightening the first article for a further gauging operation; substantially as described. 15
20. In a gauging machine, a support having a slot one dimension of which is larger than the articles to be gauged, gauge blocks having opposite gauging surfaces at the sides of the slot, and means for pressing the articles successively against the gauging surfaces; substantially as described. 25
25. In a gauging machine, a support having a slot one dimension of which is larger than the articles to be gauged, gauge blocks having opposite gauging surfaces at the sides of the slot, means for varying the distance between the gauging surfaces, and means for pressing the articles successively against the gauging surfaces; substantially as described. 30
30. In a gauging machine, a support having a slot one dimension of which is larger than the articles to be gauged, gauge blocks having opposite gauging surfaces at the sides of the slot, means for pressing the articles successively against the gauging surfaces, and means for moving an unacceptable article away from said gauging surfaces; substantially as described. 35
35. In a gauging machine, a support having a slot one dimension of which is larger than the articles to be gauged, gauge blocks having opposite gauging surfaces at the sides of the slot, means for pressing the articles successively against the gauging surfaces, and a reciprocating cam member for moving an unacceptable article from said gauging surfaces; substantially as described. 40
40. In a gauging machine, an inclined support having a slot with opposite gauging surfaces, means for feeding articles one by one down said support, and means for successively aligning the articles with and pressing them against said gauging surfaces; substantially as described. 45
45. In a gauging machine, an inclined support having a slot with opposite gauging surfaces, means for feeding articles one by one down said support, guide bars for the ends of said articles, and means for successively aligning the articles with said gauging surfaces; substantially as described. 50
50. In a gauging machine, an inclined support having a slot with opposite gauging surfaces, means for feeding articles one by one down said support, an arm for successively aligning said articles with the slot, and means for swinging said arm; substantially as described. 55
55. In a gauging machine, an inclined support having a slot with opposite gauging surfaces, means for feeding articles one by one down said support, an arm for successively aligning said articles with the slot, a spring for pressing the arm against the articles, and means for raising the arm; substantially as described. 60
60. In a gauging machine, an inclined support having a slot with opposite gauging surfaces, a slide, means for reciprocating the slide, and means actuated by said slide for successively rolling articles down said incline to the slot; substantially as described. 65
65. In a gauging machine, an inclined support having a slot with opposite gauging surfaces, an arm for successively aligning articles with the slot, a slide, means for moving the slide, and means actuated by the slide for swinging the arm and rolling the articles down said incline to the slot; substantially as described. 70
70. In a gauging machine, an inclined support having a slot with opposite gauging surfaces, an arm for successively aligning articles with the slot, a slide, means for moving the slide, a blade attached to the slide and engaging the arm to swing the latter, and means actuated by the slide for rolling articles one by one down the incline to the slot; substantially as described. 75
75. In a gauging machine, an inclined support having gauging means, a tube through which articles are fed, a member having an article receiving and restraining portion movable into and out of alignment with said tube, and means for oscillating said member to roll the articles one by one down the inclined support to the gauging means; substantially as described. 80
80. In a gauging machine, an inclined support having gauging means, a tube through which articles are fed, a member movable into and out of alignment with said tube, means for intermittently locking articles in and releasing them from said tube, 85
85. In a gauging machine, an inclined support having gauging means, a tube through which articles are fed, a member movable into and out of alignment with said tube, and means for raising the member; substantially as described. 90
90. In a gauging machine, an inclined support having gauging means, a tube through which articles are fed, a member movable into and out of alignment with said tube, and means for lowering the member; substantially as described. 95
95. In a gauging machine, an inclined support having gauging means, a tube through which articles are fed, a member movable into and out of alignment with said tube, and means for raising the member; substantially as described. 100
100. In a gauging machine, an inclined support having gauging means, a tube through which articles are fed, a member movable into and out of alignment with said tube, and means for lowering the member; substantially as described. 105
105. In a gauging machine, an inclined support having gauging means, a tube through which articles are fed, a member movable into and out of alignment with said tube, and means for raising the member; substantially as described. 110
110. In a gauging machine, an inclined support having gauging means, a tube through which articles are fed, a member movable into and out of alignment with said tube, and means for lowering the member; substantially as described. 115
115. In a gauging machine, an inclined support having gauging means, a tube through which articles are fed, a member movable into and out of alignment with said tube, and means for raising the member; substantially as described. 120
120. In a gauging machine, an inclined support having gauging means, a tube through which articles are fed, a member movable into and out of alignment with said tube, and means for lowering the member; substantially as described. 125
125. In a gauging machine, an inclined support having gauging means, a tube through which articles are fed, a member movable into and out of alignment with said tube, and means for raising the member; substantially as described. 130

and means for oscillating said member to deliver articles successively from the tube to the inclined support; substantially as described.

6 25. In a gauging machine, an inclined support having gauging means, a tube through which articles are fed, a carrier having an article receiving portion movable into and out of alignment with said tube to receive an article fed from said tube, means for successively moving articles into said receiving portion, and means for swinging said carrier to release the articles to said inclined support; substantially as described.

10 26. In a gauging machine, an inclined support having gauging means, a tube through which articles are fed, a carrier having an article receiving portion movable into and out of alignment with said tube to receive an article fed from said tube, a detent for intermittently admitting articles to said receiving portion, and means for operating the detent and the carrier to roll the articles successively down the inclined support; substantially as described.

15 27. In a gauging machine, an inclined support having gauging means, a tube through which articles are fed, a carrier having a hook member movable into and out of alignment with said tube to embrace an article fed from said tube, a detent for intermittently admitting articles to said hook member, means for swinging the carrier to roll the articles successively down the inclined support, and a yielding connection between said means and said arm; substantially as described.

20 28. In a gauging machine, an inclined support having gauging means, a tube through which articles are fed in a stream, a detent projecting into said tube to hold the endmost article, means for moving said detent to release an article, a member spaced from the end of the tube to locate said article, and means for delivering said article down the inclined support to the gauging means; substantially as described.

25 29. In a gauging machine, an inclined support having gauging means, a tube through which articles are fed in a stream, a detent projecting into said tube to hold the endmost article, means for moving said detent to release an article, a member spaced from the end of the tube to locate said article, means for delivering said article down

the inclined support to the gauging means, and a guide for the end of the article in alignment with said locating member; substantially as described.

60

30. In a gauging machine, a support having gauging means, a tube through which articles are fed in a stream, an arm having a detent for holding the endmost article, an arm having article moving means, and a reciprocating member having cams for operating the arms in time relation to intermittently deliver the articles from the tube to the gauging means; substantially as described.

70

31. In a gauging machine, a plate having a series of similar slots of different sizes, means for causing an article to pass over the plate to the different slots, and means for pressing the article against the sides of the slots; substantially as described.

75

32. In a gauging machine, an inclined support having a slot with opposite gauging surfaces, an arm having one portion to press an article against the gauging surfaces and another portion to obstruct a following article, and means for lifting the arm to admit the following article to the gauging surfaces; substantially as described.

80

33. In a gauging machine, an inclined support having a slot with opposite gauging surfaces, means for pressing an article against the gauging surfaces, and means movable through the slot to actuate the pressing means; substantially as described.

85

34. In a gauging machine, an inclined support having a slot with opposite gauging surfaces, means for pressing an article against the gauging surfaces, and a blade reciprocating through the slot to actuate the pressing means, said blade also having means to temporarily obstruct a following article; substantially as described.

90

35. In a gauging machine, an inclined support having a slot with opposite gauging surfaces, an arm having one portion to press an article against the gauging surfaces and another portion to obstruct a following article, and means for swinging the arm and temporarily obstructing the following article; substantially as described.
